(57) **CLAIM**

The ornamental design for a cold storage container, as shown and described.

DESCRIPTION

FIG. 1 is a perspective view of a cold storage container design showing my new design.

FIG. 2 is a front view of a cold storage container.

FIG. 3 is a rear view of a cold storage container.

FIG. 4 is a right side view of a cold storage container.

FIG. 5 is a left side view of a cold storage container.

FIG. 6 is a top view of a cold storage container; and,

FIG. 7 is a bottom view of a cold storage container.

Any shading and cross-hatching are not features of the design but are utilized to illustrate the surface contours of the cold storage container design in the drawings.

1 Claim, 7 Drawing Sheets
